ELECTRICAL TRANSFORMER

Dale Ander, Bronx, N. Y.

Application February 10, 1940, Serial No. 318,267

3 Claims. (Cl. 171—119)

This invention relates to electrical transformers and more particularly to variable transformers embodying a coil, the winding of which is made up of successive turns and over which turns a contact arm is mounted to travel in such manner that a contact carried thereby may be caused to traverse the successive turns of the winding for the purpose of varying the voltage of the current passing through the transformer.

Transformers of this general type are common to the art. They are generally so constituted that portions of successive turns of the winding are left bare, so that a current carrying contact can engage directly with the wire of these turns. Considerable difficulty, however, has heretofore been experienced with such transformers, due to their inability to accurately select one turn at a time. In practically every case, the movable contact has been such that a plurality of turns are bridged at all times by the movable contact or at least bridged part of the time, with the result that the turns thus bridged are short circuited. Short circuiting in this manner produces excessive heat on the contact member and materially shortens the life thereof. Furthermore arcing, which is common to prior transformers, is destructive not only of the contact, but of the turns of the winding.

The present invention is directed primarily to the movable current carrying member of the transformer, i. e., to the current carrying arm and the contact devices whereby the current is selectively conducted from the individual turns of the winding. The primary object of the invention is to provide apparatus which will select one turn at a time without detrimental short circuiting of adjacent turns at any time and capable of carrying current to one particular turn only. An important advantage of such an arrangement is that adjacent coils are not shorted by the movable contact and there is consequently absent that resistance which, in all prior transformers, has produced the undesirable heat to which I have referred.

Another object of the invention is to provide a contact member appropriate for cooperation with a transformer winding in such manner that such contact can electrically engage with only one turn at a time.

Another object of the invention is to provide a relatively high resistance bridge, so associated with the contact through which current is normally passed, that, during the period that the contact is moving from one turn to the next, this

high resistance bridge will minimize arcing at the contact.

Another object of the invention is to provide a plurality of contacts, all mounted on the same movable arm and so associated with one another that they will collectively tap and carry current from one turn of the winding at a time, without short circuiting successive turns at any time. The advantage of this arrangement is that the individual contacts may be made relatively small, but the several contacts will nevertheless collectively have sufficient surface or line engagement with any particular turn to effectually carry the current load without undue heating.

Features of the invention, other than those adverted to, will be apparent from the herein-after detailed description and claims, when read in conjunction with the accompanying drawing.

The accompanying drawing illustrates one practical embodiment of the invention, but the construction therein shown is to be understood as illustrative, only, and not as defining the limits of the invention.

Figure 1 is a fragmentary perspective view showing the present invention incorporated in transformer construction.

Figure 2 is a longitudinal central vertical section in the plane of the line 2—2 of Figure 1, with associated contacts in elevation and cooperating with a portion of a turn of the winding.

Figure 3 is a like section in the plane of the line 3—3 of Figure 2, showing details of the high resistance bridge.

Figure 4 is a perspective detail of a carrier for the bridge roller.

Figure 5 is a like view of brush holder employed.

Figure 6 is a diagrammatic perspective showing the manner in which the contacts cooperate with adjacent turns of the coil.

The present invention may be associated with either a cylindrical winding or a straight winding and it is not limited to the particular type of transformer with which it may be employed. However, for the purpose of illustration, I have shown the invention in Figure 1 as associated with a cylindrical winding, a number of turns of which are indicated by the reference character 1. These turns, which constitute a succession of current carrying members, are wound about a suitable core of annular form with appropriate end plates 2 and between the end plates 2 the turns are uncovered for cooperation with a movable contact of the transformer. The turns are, however, insulated with respect to one another

in any suitable and conventional way. Transformers of this type commonly have a movable arm 3 comprising sections 3a and 3b, the latter of which is carried by a coaxial pivot 4. An insulation strip 5 is interposed between these sections, whereby that portion of the arm, which carries the movable contacts, is insulated from the pivot. Current is fed to the movable contacts through a cable lead 6. The structure, as thus far described, may be conventional and no claim is made thereto, apart from the present invention which will now be explained in detail.

According to the present invention, there is mounted rigidly at the outer end of the arm 3 a contact holder 7. This contact holder is of hollow rectangular form and has an open bottom. In the holder is seated one or more contacts C and C'. Two such contacts are shown, although more or less may be employed without departing from this invention. In any event, they are mounted snugly within the holder for sliding movement radially of the transformer winding and each is individually sprung pressed by a spring 8 positioned between the closed top of the holder and the contact, as shown best in Figure 2. Although it is not essential, it is preferable that each of the springs 8 terminates at both ends in axial projections 9 received in sockets in the holder and contact, respectively, so as to center the spring in order that it may axially contact to yieldably force the contact in the direction of the turn 1 of the winding, as shown in Figure 2.

Each contact carries a binding post 10 and these binding posts extend through slots 11 in the side of the holder and are connected to woven wire pigtail current leads 12 which form branches of the main lead 6. The contacts or leads 12 are not insulated from the section 3a of the arm 3, so that said section of the arm is "live."

The contacts are illustrated in perspective in Figure 6. Each embodies a metal contact strip 14, in face abutting relation with one side of which is an insulating strip 15 of any suitable dielectric material, for example, mica, and on the distant side of the insulating strip is a metal face plate 16. In face abutting relation to the back surface of the contact strip 14 is a metallic filler block 17 and the binding post 10 is in the form of a bolt, passing through the entire assembly with a countersunk head with a nut 18 serving to bind all of the parts together, so that they become a rigid unit. The lower ends of the contact strip 14 and the insulating strip 15 are collectively chamfered or beveled to form a wedge shape, indicated at 19, and adapted to extend below the lower edge of the filler block to cooperate with the successive turns 1 of the winding, after the manner shown in Figure 6.

The contacts are positioned in the holder 7 in the reversed relation shown in Figure 6, with their wedge shaped end extending into the adjacent spaces between the consecutive turns 1, 1a and 1b of the winding and with the spacing between the apices of such wedges slightly less than the distance between centers of the consecutive turns of the winding. This is the normal current-carrying position of the parts. With the contacts at rest, the contact plates 14 of the contacts C and C' will be in electrical engagement with the turn 1a, while the dielectric strips 15 of these two contacts insulate the plates 14 from contact with the turns 1 and 1b, adjacent to but on opposite sides of the current carrying turn 1a. When the parts are in this position, short circuit-

ing between consecutive turns is impossible and current will be fed to the intermediate turn 1a to the exclusion of all other turns.

When the parts are in current carrying relation to any particular turn, both the contacts C and C' will carry part of the current from that turn and thus minimize resistance to current flow with consequent minimum heating.

When the arm 3 is moved as described, there are intervals, as the contacts pass to successive turns, when the current flow is interrupted. In the handling of high voltages, this may cause a tendency to undesirable arcing. I have therefore shown in the drawing means whereby this may be minimized and practically eliminated. I accomplish this result by associating with the movable arm a roller 20 of carbon or some other resistance material capable of carrying current and bridging the consecutive turns, but with its resistance so high that, when the metallic parts of the contacts C and C' are in engagement with one turn of the winding, all the current will flow through these contacts rather than through the high resistance roller 20.

The roller 20 is supported for rotation in a yoke 21 mounted for movement radially of the coil within the confines of a housing 22. This housing holds the yoke against lateral movement and is in turn rigid with the arm 3. Studs 23 on the yoke extend loosely through holes in the housing and arm and guide it for such radial movement while springs 24 hold the roller in contact with the coil. The roller is supported within the yoke on a spindle 25, the outboard end of which carries a conducting roller 26 and with this roller cooperates a brush 27 carried by a brush holder 28 supported on the yoke 21, all as clearly shown in Figures 3, 4 and 5. The brush has a pigtail connection with the arm 3 to ground the same thereon.

As the movable arm 3 is rotated about the pivot 4, the high resistance roller 20 will traverse the turns of the winding in succession, at all times bridging two adjacent turns of the winding on the low voltage side of the turn which the contacts are leaving. In this manner arcing is practically eliminated.

Experience has shown that by the use of a plurality of contacts constructed as described, and the concurrent employment of the high resistance roller bridge, the structure will have an unbelievably long life. This is due to the fact that there is very little heating of the contacts C and C' and, because of the absence of arcing, there is relatively little pitting or burning away thereof. The spring actuated contacts move over the several turns in succession after the manner of a ratchet and the pressure of the springs behind these contacts serve to hold the movable arm in any current carrying position in which it may be placed.

I have shown in the drawing the preferred form of this invention embodying two contacts C and C', reversed with respect to one another, so as to electrically cooperate with the opposite sides of one turn at a time. If desired, however, I may position these contacts in the holder in the same relation, i. e., not reversed. When this is done, the same sides of both contacts will cooperate with the same side of one winding at a time and a satisfactory result will be obtained. I prefer, however, to use the structure as shown in the drawing, as it appears to better distribute the wear and to produce a better balance in the operation of the structure.

In the drawing the contacts of this invention are shown as cooperating directly with the turns of a transformer winding. I may, however, if desired take taps off of successive turns of a transformer and lead them to current carrying members arranged in spaced relation and then have the contacts and cooperating resistance roller cooperate with these current carrying members instead of directly with the turns of the transformer. In other words, the present invention is useful either directly with the winding of a transformer or with current carrying members connected thereto.

The foregoing detailed description sets forth the invention in its preferred practical form, but the invention is to be understood as fully commensurate with the appended claims.

Having thus fully described the invention, what I claim as new and desire to secure by Letters Patent is:

1. An electrical transformer comprising an annular winding of substantially circular wire having turns with a portion of each turn uncovered for cooperation with movable contacts, a movable arm pivoted coaxially of the annular winding to travel circumferentially thereof, a pair of spring pressed contacts carried by the arm and impelled into engagement with the uncovered portion of said winding, each of said contacts comprising conductive and dielectric strips positioned back to back and rigidly secured to one another with their winding-engaging ends collectively wedge shaped to fit between successive turns of the winding with the conductive strip in electrical engagement with one turn and the associated dielectric strip in dielectric engagement with the next adjacent turn of the winding, the several contacts being so positioned on said arm that the apices of their wedge shaped ends are spaced apart in a direction circumferentially of the winding a distance less than the distance between centers of the consecutive turns of the winding, and with the conductive strips of the several contacts arranged in directions facing a common interposed turn of the winding to simultaneously engage with the opposite sides thereof.

2. An electrical transformer comprising an annular winding of substantially circular wire having turns with a portion of each turn uncovered for cooperation with movable contacts, a movable arm pivoted coaxially of the annular winding to travel circumferentially thereof, a pair of spring pressed contacts carried by the arm and impelled into engagement with the uncovered portion of

said winding, each of said contacts comprising conductive and dielectric strips positioned back to back and rigidly secured to one another with their winding engaging ends collectively wedge shaped to fit between successive turns of the winding with the conductive strip in electrical engagement with one turn and the associated dielectric strip in dielectric engagement with the next adjacent turn of the winding, and a roller carried by said arm in electrical connection with said contacts and spring pressed into engagement with the uncovered portion of the winding, said roller having a relatively high resistance as compared to the current carrying strips of said contacts and positioned to engage with the same turn of the winding as is engaged by the conductive strips of the contacts and also one adjacent turn.

3. An electrical transformer comprising an annular winding of substantially circular wire having turns with a portion of each turn uncovered for cooperation with movable contacts, a movable arm pivoted coaxially of the annular winding to travel circumferentially thereof, a pair of spring pressed contacts carried by the arm and impelled into engagement with the uncovered portion of said winding, each of said contacts comprising conductive and dielectric strips positioned back to back and rigidly secured to one another with their winding engaging ends collectively wedge shaped to fit between successive turns of the winding with the conductive strip in electrical engagement with one turn and the associated dielectric strip in dielectric engagement with the next adjacent turn of the winding, the several contacts being so positioned on said arm that the apices of their wedge shaped ends are spaced apart in a direction circumferentially of the winding a distance less than the distance between centers of the consecutive turns of the winding, and with the conductive strips of the several contacts arranged in directions facing a common interposed turn of the winding to simultaneously engage with the opposite sides thereof, and a roller carried by said arm in electrical connection with said contacts and spring pressed into engagement with the uncovered portion of the winding, said roller having a relatively high resistance as compared to the current carrying strips of said contacts and positioned to engage with the same turn of the winding as is engaged by the conductive strips of the contacts and also one adjacent turn.

DALE ANDER.
